DISPENSER FOR LIQUIDS AND FLUIDISED POWDERS

David J. V. Smith, Crowthorne, England, assignor to Graviner (Colnbrook) Limited, London, England, a
British company

Filed Aug. 10, 1966, Ser. No. 3,412

Term of patent 14 years

(Cl. D62—2)

Fig. 1.

Fig. 2.

Fig. 3.

Fig. 4.

FIGURE 1 is a perspective view from the rear of a dispenser for liquids and fluidised powders showing my new design;

The dominant features of my design reside in the portions shown in full lines.

I claim:

The ornamental design for a dispenser for liquids and fluidised powders, as shown and described.
